S. COHEN

RADIO FREQUENCY TRANSFORMER

Filed Jan. 27, 1923

INVENTOR.

Samuel Cohen
Cornelius D. Elbert
his ATTORNEY.

UNITED STATES PATENT OFFICE.

SAMUEL COHEN, OF BROOKLYN, NEW YORK.

RADIOFREQUENCY TRANSFORMER.

Application filed January 27, 1923. Serial No. 615,210.

To all whom it may concern:

Be it known that I, SAMUEL COHEN, a citizen of the United States, residing in Brooklyn, county of Kings and State of New York, have invented certain new and useful Improvements in Radiofrequency Transformers, of which the following is a specification.

My invention relates to transformers for utilization in connection with circuits traversed by high frequency currents, and particularly currents of radio frequency, as utilized in radio telegraph, telephone or other systems.

In accordance with my invention, the transformer structure is of general application, but is particularly utilizable as an inter-valve transformer, as for coupling the anode circuit of a thermionic device, as of the audion type, with the grid or control electrode circuit of a succeeding stage of an amplifying system.

In accordance with my invention, the width or thickness, or axial length, of the transformer coils is small, and preferably very small as compared with the diameter of the coil, this relation effecting high inductance and low distributed capacity, both of which are desiderata in transformers of this type.

In accordance with my invention, the primary and secondary coils are wound upon suitable supports or forms, in suitably close relation to each other, side by side, the material of the support or form being such as has low dielectric constant, and further to reduce capacity effects the form or support is suitably cut away, skeletonized or otherwise reduced as to the total mass of form or support material present in association with the coils, and preferably adjacent them or between them.

My invention resides in a transformer of the character hereinafter described and claimed.

For an illustration of one of the various forms my invention may take, reference may be had to the accompanying drawing, in which:

Fig. 1 is a top plan view of structure embodying my invention.

Figs. 2 and 3 are sectional views, partially in elevation, taken on the lines 2—2 and 3—3, respectively, of Fig. 1.

Fig. 4 is a side elevational view of the winding support or form.

Fig. 5 is a sectional view of the same.

Fig. 6 is a side elevational view of the form with the windings wound thereon.

Fig. 7 is an end elevation of the form with the windings thereon.

Fig. 8 is a diagrammatic view illustrating one of the various uses of my invention.

Referring first to Fig. 8, P is the primary of a radio frequency transformer connected in the anode circuit of a thermionic amplifier or similar device V, comprising the filament or cathode f, grid g and anode or plate a. The coil L, which may be the secondary of a coupling transformer, or a coil itself directly absorbing electro-radiant energy from the natural media, is shunted by a tuning condenser C, and the grid g and filament f of the amplifier V are connected to opposite terminals of the coil L and condenser C, as well understood in the radio art. The filament f is heated to incandescence by current from the battery A controlled by the rheostat r. In the circuit of the anode a, in addition to the aforesaid primary P, is the source of current or battery B. The currents of high or radio frequency impressed upon the grid circuit of the tube V are amplified thereby and appear in greater amplitude in the primary P, which inductively affects the secondary coils S and S¹, cumulatively affected by the primary P and aiding their electromotive forces in influencing the potential of the grid g of the second thermionic device V¹, which may be an amplifier, as shown, or may be a detector or other type of device.

My invention relates to the transformer comprising the primary P and one or more of the secondary coils S, S¹.

It is desirable for best operation that the inductance of the primary and secondary coils be high, and that nevertheless their capacities, as distributed capacities, shall be low. To this end, the coils are made axially short, narrow, or thin, and of a diameter which is great compared with the width or thickness.

For this purpose there is provided a form or support F, Figs. 2 to 7 inclusive, of fibre, ebonite, hard rubber or other suitable material, preferably a material whose dielectric constant is low or sufficiently low for the purposes involved.

The form is provided with a circumferential groove or slot p, in which is wound the primary coil P, as indicated in Fig. 7. Adjacent

cent the groove or slot p is a circumferentially extending groove or slot s , in which is wound the secondary coil S . Where suitable or desired, the secondary winding as a whole may be divided into two parts S and S^1 , as indicated in Fig. 8. In such case the form F may be provided with a third slot or circumferential groove s^1 , in which is wound the secondary coil S^1 , as indicated in Fig. 7.

It will accordingly be noted that the width or thickness of each of the coils is very small as compared with the diameter, this general proportion effecting high inductance and low distributed capacity. By way of example, it may be stated that the primary coil P may consist of 131 turns of No. 40 enameled copper wire, while each of the coils S and S^1 consists of 100 turns of No. 20 enameled copper wire, whereby the total of the secondary turns is 200. Each of the slots p , s and s^1 is approximately .032 inch in width, and the internal diameter of each of the slots, and therefore of each of the coils P , S and S^1 is approximately $\frac{5}{8}$ of an inch.

Further to reduce the distributed capacity, the mass or amount of the material of the form F is reduced. This, in the example illustrated, is accomplished by boring through the form F the holes H , suitably spaced circumferentially of the form F in suitable number and size, and preferably forming reductions of material adjacent the windings or coils themselves, as indicated in Fig. 6. In other words, the holes H intersect the winding slots p , s and s^1 . The material of the form F may be otherwise suitably reduced, particularly adjacent the actual windings themselves.

Conveniently to bring out the ends or terminals of the primary and secondary windings, there may be provided the transversely extending slots b , suitably spaced from each other circumferentially of the form F in a number suitable for bringing out the number of coil ends or terminals involved.

While I have indicated the transformer as comprising a single primary and two secondary coils, it will be understood that there may be employed more than one primary coil and either one secondary coil or any greater number.

The example above given is for a radio frequency transformer suitable for inter-valve or inter-amplifier use in connection with wave lengths ranging from about 175 to 650 meters.

The same general features and ideas of construction may be utilized, however, for longer wave lengths.

In the example illustrated in connection with the aforesaid shorter wave lengths, the inductance of the primary P may range from about .52 to about 1.2 milli-henrys,

while the inductance of the secondary may range from about .875 to 2.2 milli-henrys, these values varying within the ranges indicated for variations of inter-electro capacity within the valves or audions themselves. Furthermore, in accordance with the examples of dimensions and structure above given, the distributed capacity of the transformer coils is low and within a range from about .5 to about 1.5 micro-microfarads.

Features of my invention are also utilizable in connection with audio frequency transformers, in which case the inductance of each of the windings of the transformer may be of the order of $\frac{1}{2}$ henry with a distributed capacity of the order of 2 micro-microfarads.

The winding unit as indicated in Fig. 7 having been completed, it may be suitably mounted or housed, as by recourse to structure as follows: a housing or hollow member D of insulating material, preferably molded material, as condensite, bakelite or the like, has a chamber E in which the form or support F , carrying the windings, is placed, as indicated in Figs. 2 and 3, in such position that the coil ends or terminals extending through the different slots b are suitably positioned for connection with particular binding posts intended therefor. Thus, the form F is placed in such position in the cavity E that the different slots b come opposite or adjacent the proper ones of the four binding posts, I, J, K and M.

These binding posts comprise screws c extending upwardly through the member D from the recesses N , through the washers d . Threaded upon each screw is a locking washer or nut e , between which and the finger nut h , threaded upon the screw, may be held and bound a circuit connection or conductor.

After placing the form F in the position indicated in Figs. 2 and 3, the metallic holding strips or lugs i are placed in position and the screws c passed therethrough and the member D as aforesaid, the screws c when tightened holding the lugs i snugly and firmly in position and thereby holding the form F in desired position. To these lugs i may be connected the aforesaid ends or terminals of the windings or coils P , S and S^1 , thereby effecting electrical communication with their respective binding posts.

Thereafter the chamber 1 and the recesses N may be filled with molten insulating material which on cooling solidifies. For example, paraffine and beeswax may be employed, or any other suitable or equivalent material, the same being indicated at j . When the transformer is to be utilized for short waves, as, for example, those ranging from about 175 to about 650 meters, it is preferred that no material j be introduced or used, since its close approach to the wind-

ings will tend to increase to undesired extent the distributed capacity of the windings. However, for the longer wave lengths material *j* may be used, but even in the case 5 of the longer wave lengths it may be omitted.

In the member *D* are molded the interior-
ly threaded metallic inserts *k*, into which
10 are threaded the screws *m* to hold in place
the bottom plate *n* having the integral lugs
or ears *o* having holes *q* to accommodate
screws for holding the structure to any suit-
able base or support.

It will be noted concerning the construc-
tion hereinbefore described that there is no
metallic or conducting part disposed in or
close to the fields of the transformer wind-
ings. It is desirable to avoid the presence of
20 metallic or conducting material in the fields
in order to prevent an increase of the ap-
parent resistance of the coils or circuits, such
increase of resistance increasing the losses,
which should be kept as low as possible.

What I claim is:

25 1. Transformer structure of the character
described, comprising a housing of insulat-
ing material having a chamber, a trans-

former unit disposed in said chamber and
comprising a plurality of grooves and wind-
ings in said grooves, conducting members
30 projecting from opposite sides of said
chamber over said unit within said housing,
connections from said coils to said conduct-
ing members, and binding posts extending
35 through said conducting members to the exterior
of said housing.

2. Transformer structure of the character
described, comprising a housing of insulat-
ing material having a chamber, a trans-
former unit disposed in said chamber and
40 comprising a plurality of grooves and wind-
ings constituting a pair of secondary coils
and an intermediate primary coil in said
grooves, conducting members projecting
from opposite sides of said chamber over
said unit within said housing, connections
from said coils to said conducting members,
and binding posts extending through said
conducting members to the exterior of said
housing.

In testimony whereof I have hereunto af-
fixed my signature this 22d of January,
1923.

SAMUEL COHEN.
